CLAIM

The ornamental design for a handbag as shown and described.

DESCRIPTION

FIG. 1 is a front perspective view of the handbag, showing the new design;

FIG. 2 is a front view thereof;

FIG. 3 is a rear view thereof;

FIG. 4 is a left side view thereof;

FIG. 5 is a right side view thereof;

FIG. 6 is a top view thereof; and,

FIG. 7 is a bottom view thereof.

The thick broken lines in the drawings represent stitching and form no part of the claimed design. The thin broken lines in the drawings represent environmental structure and form no part of the claimed design.

1 Claim, 7 Drawing Sheets
